MACHINE FOR FINISHING EDGES OF
UNDERPADDINGJack C. Gordon, Detroit, Mich., assignor to Allen
Industries, Inc., Detroit, Mich., a corporation of
Delaware

Application May 7, 1941, Serial No. 392,381

6 Claims. (Cl. 164—73)

This invention relates generally to machines for forming and finishing the edges of underpadding for carpets, rugs and the like and refers more particularly to a machine for forming and sealing the edge portions of the underpadding.

Heretofore the edges of underpadding have been vertical or at right angles to the top and bottom surfaces thereof and have been provided with stitching, facing or binding to prevent the material of the underpadding from raveling or working loose. Thus, considerable labor, time, and handling, as well as material such as tape, thread, and the like, were required in a factory to accomplish the desired results. Even then, the finished product had relatively sharp corners or abrupt edges which prevented the carpet or rug thereon from draping or falling properly onto the floor.

In the present instance I have overcome the difficulties encountered with the old constructions by providing the underpadding with beveled pressure sealed edges that not only obviate all sewing operations and thus eliminate the labor, handling, time and material expense referred to above, but that also take the place of the usual abrupt right angles edges in the finished product and thus permit the carpet or rug thereon to drape or fall gradually onto the floor. Hence, I have provided an underpadding with an improved edge formation that effects a definite economy in manufacturing costs, that possesses many advantages over the conventional edge construction, and that provides a worthwhile sales appeal in the industry.

Thus, it is an object of the present invention to provide a machine for forming to the configuration desired the edges or edge portions of underpadding and for sealing such formed edges with a suitable adhesive substance so that such configuration will be effectively maintained.

Another object is to provide a machine that has means for forming and sealing transverse as well as longitudinal edges of the underpadding.

Another object is to provide a machine wherein a single set of rolls will suffice to form and seal the transverse edges aforesaid.

Another object is to provide a machine wherein means is provided for synchronizing the motion of the rolls for forming and sealing the transverse edges.

Another object is to provide a machine wherein two sets of rolls located respectively at opposite sides of the underpadding are provided to form and seal the longitudinal edges and that are preferably driven from a single shaft.

Another object is to provide a machine wherein the two sets of rolls just mentioned may be spaced or adjusted laterally relative to each other to accommodate underpadding of different widths.

Other objects, advantages and novel details of construction of this invention will be made more apparent as this description proceeds, especially when considered in connection with the accompanying drawings, wherein:

Figure 1 is a top plan view of a machine embodying my invention;

Figure 2 is a longitudinal side elevation of the structure shown in Figure 1;

Figure 3 is an end elevation of the structure shown in Figure 2;

Figure 4 is a diagrammatic view of the means for synchronizing the motion of the upper and lower carriages;

Figure 5 is a top plan view of one set of rolls and associated parts for forming and sealing one of the longitudinal edges of the underpadding;

Figure 6 is an end view of the structure illustrated in Figure 5;

Figure 7 is a side elevation of the structure illustrated in Figures 5 and 6;

Figure 8 is a sectional view taken substantially on the line 8—8 of Figure 5;

Figure 9 is a sectional view taken substantially on the line 9—9 of Figure 5;

Figure 10 is a top plan view of the single set of rolls for forming and sealing the transverse edges of the underpadding;

Figure 11 is a vertical sectional view through the structure illustrated in Figure 10;

Figure 12 is a side elevation of the structure shown in Figure 10;

Figure 13 is an end view of a slight modification;

Figure 14 is a side elevation of the structure illustrated in Figure 13.

Referring now to the drawings, A is a sheet of underpadding formed of fibrous material and having pressure sealed beveled edges 10, and B is a machine for providing the underpadding with such beveled edges.

As usual, the underpadding A has a flat or plain lower surface 11 for engagement with a floor and has a felted upper surface 12 for supporting engagement with the underside of a carpet or rug. The beveled edges 10 of the underpadding are compressed to the form shown and are sealed and held in this formation by a suitable adhesive such as latex or aqueous dispersions of rubber. The usual colloidal latices may be used.

as well as various types of dispersions. Various solutions of latex containing different percentages of solids in colloidal solution may be used depending upon the thickness of the coating or seal desired. Such coatings may be used with or without a coagulating agent as desired. Actually I rely upon the viscosity of the adhesive to which the compressed beveled edges are subjected to seal and hold them in such beveled formation.

The machine B has two sets C and D, respectively, of rolls for forming and sealing the longitudinal edges of the underpadding, and has a single set E of rolls for forming and sealing the transverse edges of said underpadding.

As shown, the sets C and D of rolls are spaced laterally apart and are similar in construction. Preferably each set has four horizontal shafts 13, 14, 15 and 16, respectively, arranged in vertically spaced pairs within a supporting frame 17.

The shafts 13 and 14 are provided at one end with meshing gears 18 and 19 and are provided at their other end with rolls 20 and 21 having oppositely beveled surfaces 22 and 23, respectively, that are engageable with the upper and lower surfaces of the underpadding to squeeze or compress the material thereof into substantially V cross section. The lower roll 21 is preferably wider than the upper roll 20 and carries the liquid adhesive, such as a latex solution, from a pan 24 to the underside of the underpadding as the latter is compressed by the rolls 20 and 21.

The shafts 15 and 16 are provided at one end with meshing gears 25 and 26 and are provided at their other end with rolls 27 and 28 that cooperate with each other to cut the underpadding along a predetermined line. Preferably a hardened tool steel knife 30 is carried by the upper roll 27 and has its cutting edge 31 at the flat periphery 32 of the lower roll 28. In this connection, it will be noted that the knife 30 is clamped between sections of the roll 27 and is held in place by bolts 33. The cutting edge 31 is substantially V-shape in cross section and constitutes a circumferentially extending rib on the periphery of the roll 27. Such periphery is preferably knurled as shown upon opposite sides of the knife 30 to insure proper non-slip engagement of the roll with the underpadding. Moreover, it will be noted that the arrangement of shafts and rolls is such that the rolls 27 and 28 carried by the shafts 15 and 16 are in tandem with the rolls 20 and 21 carried by the shafts 13 and 14 so that the actual cutting of the underpadding by the rolls 27 and 28 will be substantially in line with the apex of the V formation of the underpadding after it has been made by the rolls 20 and 21.

As shown, the shafts 13 to 16, inclusive, are journaled in bearings 34 carried by the supporting frame 17. Preferably the bearings 34 for the upper shafts 13 and 15 are adjustable by bolts 35 extending through the top bar 36 of the frame and are held in position by nuts 37 and 38 on said bolts above and below the bar. Hence, the pressure exerted by the upper rolls 18 and 25 upon the underpadding may be conveniently adjusted as desired.

To insure rotation of the rolls 20, 21, 27 and 28 in the proper direction and at the proper time, there is an endless chain 40 trained around sprockets 41 fixed to the upper shafts 13 and 15. Moreover, as it is desirable to have the rolls of the two sets C and D move in unison, there is a shaft 42 extending across the machine and pro-

vided adjacent the respective sets C and D with sprockets 43. Endless chains 44 connect these sprockets 43 to suitable sprockets 45 on the upper shafts 15 of the respective sets C and D. Thus, the shaft 42 constitutes a common drive for both sets C and D and may be operated by and under the control of any suitable means (not shown) so that its operation may be regulated as desired.

In order that the sets C and D may be adjusted relative to each other transversely of the machine to accommodate various widths of underpadding, the base 46 of each frame 17 has a tongue and groove connection with a supporting base 47 carried by I-beams 48 mounted upon structural bars 49. Thus, sliding movement of the base 46 relative to the base 47 transversely of the machine is provided by this construction. Any suitable means (not shown) may be employed to hold or maintain the bases 46 in adjusted position relative to the base 47. In this connection it will also be noted that the latex pans 24 are carried by the slideable bases 46 and therefore move therewith when any adjustment is made.

The single set E of rolls is preferably mounted to move across the machine in rear of the sets C and D of rolls from one longitudinal edge to the other of the underpadding to form and seal the transverse edges thereof. As shown, this set E comprises two cooperating rolls 50 and 51 on shafts 52 and 53 journaled in bearings 54 bolted or otherwise secured to carriages 55 and 56, respectively, that are slideable along track rails 57, 58, 59, 60, 61 and 62, respectively. Preferably the upper roll 50 carries a hardened tool steel knife 63, while the lower roll 51 carries a hardened tool steel insert 64. The peripheries of the rolls 50 and 51 are beveled or inclined as illustrated so that the material of the underpadding will be compressed to substantially V cross section. The cutting edge 65 of the knife projects only slightly from the periphery of the upper roll 50 so as to constitute a circumferentially extending rib and is adapted to cooperate with the hardened insert 64 to effect the cutting operation. Thus, with this construction the forming and cutting operations are performed substantially simultaneously by the rolls 50 and 51 as they travel across the underpadding. The lower roll 51 rotates in a pan 66 containing the adhesive solution so as to conduct such solution from the pan to the underside of the underpadding. Preferably this pan 66 is supported upon a part of the lower carriage 56 so as to move therewith.

To provide proper non-slip engagement between the underpadding and the rolls 50 and 51, there are auxiliary rolls 70, 71, 72 and 73, respectively, arranged upon opposite sides of the rolls 50 and 51. As shown, the upper auxiliary rolls 70 and 71 constitute lateral extensions of the roll 50 and have knurled peripheries for proper non-skid engagement with the underpadding, while the lower auxiliary rolls 72 and 73 are spaced laterally from the roll 51 and are fixed to the shaft 53.

To provide synchronized movement of the upper and lower carriages 55 and 56, there is an endless chain 74 fastened to the carriages 55 and 56 and trained about eight sprockets 75, as illustrated in Figure 4. One of these sprockets constitutes the drive means for the chain 74, and for this purpose is fixed upon a shaft 76 of a suitable reduction gearing 77 operatively connected to a drive shaft 78 of a reversible electric motor 79. Any suitable means (not shown) for

controlling the operation of the motor 79 may be employed.

To obtain the proper driving action for the rolls 50 and 51 there are gears 80 fixed to the shafts 52 and 53 at opposite ends thereof and meshing with pinions 81 that engage rack strips 82 fixed to and extending longitudinally of suitable frame members 83 and 84, respectively. Any suitable shafts, such as 85, may be provided in the carriages 55 and 56 for the pinions 81 so that the latter will cause the gears 80 to rotate the shafts 52 and 53 as the pinions 81 travel along the rack strips 82.

In the present instance the lower track rails 61 and 62 are supported on top of I-beams 86 mounted on the structural members 49, while the upper track rails 57, 58, 59 and 60, respectively, are suspended from I-beams 87 supported from one or more structural members 88. Actually the structural members 49, beams 48 and 86, respectively, and base 47 cooperatively form or constitute the bed of the machine and carry all but the suspended elements of the machine.

In use, the underpadding made in sheet form in the usual manner moves from left to right of the machine as illustrated by the arrow in Figure 1 so as to be engaged first by the squeeze rolls 20 and 21 of both sets C and D which not only compress the material of the underpadding to provide V-shaped formations, but also cause the liquid adhesive transferred by the lower rolls 21 from the pans 24 to the underside of the underpadding to be squeezed through the material of the underpadding to impregnate the V formation and thus provide an adhesive film on the upper inclined surface 10^a as well as upon the lower inclined surface 10^b of the V formation. Further movement of the underpadding to the right causes the rolls 27 and 28 of both sets C and D to cut the underpadding adjacent the apexes of the V's to provide the beveled longitudinal edges of the underpadding. Further movement of the underpadding to the right places it in position to be engaged by the rolls 50 and 51 of the single set E to form one transverse beveled edge of the underpadding. This is accomplished by stopping temporarily the drive shaft 42 and by starting the normally idle motor 79 to cause the carriages 55 and 56 carrying the rolls 50 and 51 to be moved in one direction across the underpadding. The motor 79 is then stopped and the shaft 42 is again started to cause further advancement of the underpadding to the right. When it is desired to form the second transverse edge of the underpadding, the shaft 42 is again stopped and the motor 79 is started so that the carriages 55 and 56 will move in the opposite direction across the underpadding. As the carriages 55 and 56 move back and forth as described, the rolls 50 and 51 will perform substantially simultaneously three operations, i. e., compression of the material of the underpadding to V cross section, severing or cutting of the material at the apexes of the V's, and impregnation of the V's with the adhesive liquid. After all four edges of the underpadding are formed, the latter is then placed in a dryer (not shown) so that the liquid adhesive will be transformed into a resilient binder for the compressed material to effectively maintain the shape of the beveled formations. Thus, when the underpadding comes out of the dryer, it is a finished product ready to be wrapped in the usual manner for shipping purposes.

In Figures 13 and 14 I have illustrated a slight modification wherein only one set 90 of rolls is

employed. As shown, this set 90 is identical with the single set E, except that the shafts 91 and 92 for the rolls 93 and 94 are mounted in a frame 95 in the same way that the shafts 15 and 16 of the set D are mounted, and have at one end meshing gears 96 and 97 for establishing a driving connection between said shafts. Also a drive shaft 98 may be connected to the shaft 91 by a chain 99 trained about sprockets 100 and 101 on the shafts 91 and 93. Thus, with this construction a sheet of underpadding may be provided wherever desired with a beveled edge of the type described by simply moving such sheet in the desired manner relative to the rolls 93 and 94. In this as well as in the structure previously described, any suitable table or conveyer (not shown) may be employed to support the underpadding while being passed through the machine.

What I claim as my invention is:

1. A machine of the class described having upper and lower track rails, carriages movable along said rails, cooperating rolls carried respectively by said carriages, and actuating means for said carriages including a plurality of spaced sprockets, and an endless chain trained around said sprockets and having portions thereof connected to said carriages, a drive shaft for one of said sprockets, and means for driving said shaft.

2. A machine of the class described having a frame, upper and lower track rails carried by said frame, carriages movable along said rails, shafts journaled in said carriages, one in each carriage, cooperating rolls on said shafts, one on each shaft, and actuating means for said carriages including a plurality of spaced sprockets, an endless chain trained around said sprockets and having portions thereof connected to said carriages, a drive shaft for one of said sprockets, and actuating means for the rolls including racks carried by the frame, pinions on the carriages meshing with the racks, and gears on the shafts for the rolls and meshing with said pinions.

3. In a machine of the class described, a frame, upper and lower tracks carried by said frame, separate carriages movable along said tracks, one along the upper track, and one along the lower track, shafts carried by said carriages, one shaft to each carriage, rolls fixed to said shafts having means for compressing a portion of a fibrous sheet to substantially V cross section and having means for severing the sheet at the apex of the V formation, means for synchronizing the movement of said carriages, rack bars fixed to said frame, gears on said shafts, and pinions meshing with said rack bars and gears and operable when the carriages move along said tracks to rotate said gears, shafts and rolls.

4. A machine of the class described having a bed, two laterally spaced upright frames on said bed, front and rear pairs of vertically spaced horizontal shafts in each of said frames, cooperating rolls carried by the vertically spaced shafts of the front pair in each frame and having means for compressing longitudinally extending portions of the underpadding to substantially V cross section, cooperating rolls carried by the vertically spaced shafts of the rear pair in each frame and having means for severing the underpadding at the apexes of the V formations to provide the underpadding with longitudinal edges of V cross section, upper and lower horizontal track rails extending across the bed at one side of the laterally spaced frames, upper and lower carriages slideable along said rails from one

longitudinal edge to the other of the underpadding, horizontal shafts journaled in said carriages, one in each carriage, and cooperating rolls carried by the last mentioned shafts and having means for compressing a transversely extending portion of the underpadding to substantially V cross section and having means for severing the underpadding at the apex of the V formation to provide the underpadding with a transversely extending edge of V cross section. 10

5. A machine of the class described having a bed, upper and lower horizontal track rails extending across the bed, upper and lower carriages slideable along said rails, horizontal shafts journaled in said carriages, one in each carriage, cooperating rolls carried by said shafts and having means for compressing a portion of a fibrous sheet to substantially V cross section and having means for severing the fibrous sheet at the apex of the V formation, means providing synchronized movement of the upper and lower carriages back and forth along said track rails, 15

10 15 20

and means for rotating in unison the shafts in said carriages as the latter moves along said rails.

6. A machine of the class described having a bed, upper and lower horizontal track rails extending across the bed, upper and lower carriages slideable along said rails, horizontal shafts journaled in said carriages, one in each carriage, cooperating rolls carried by said shafts and having means for compressing a portion of a fibrous sheet to substantially V cross section and having means for severing the fibrous sheet at the apex of the V formation, means providing synchronized movement of the upper and lower carriages back and forth along said track rails, and means for rotating in unison the shafts in said carriages as the latter moves along said rails, including racks extending along the rails, gears on the shafts, and pinions carried by the carriages and meshing with the racks and gears.

JACK C. GORDON.
